UNITED STATES PATENT OFFICE.

JOSEPH J. MARIOTTI, OF CHICAGO, ILLINOIS, ASSIGNOR TO DAPRATO STATUARY COMPANY, OF CHICAGO, ILLINOIS, A CORPORATION OF ILLINOIS.

SAFE LOCK.

Application filed March 12, 1925. Serial No. 14,864.

To all whom it may concern:

Be it known that I, JOSEPH J. MARIOTTI, a citizen of the United States, residing at Chicago, in the county of Cook and State of Illinois, have invented certain new and useful Improvements in Safe Locks, of which the following is a specification.

This invention relates to locking mechanisms for safes and more particularly to locking mechanism for double door safes or vaults for tabernacles or other uses.

A primary object of this invention is to provide a simple and inexpensive, yet efficient and reliable locking mechanism where-
15 by the double doors of safes may be securely locked together and to the frame or body of the safe.

Another object is to provide a safe door locking mechanism which may be operated
20 by an ordinary tumbler release or other key for operating the locking bolts and for swinging the doors without the provision of handles, knobs, or the like, commonly used for the purpose.

25 Further objects and advantages of the invention will appear from the description and claims and from the drawing in which:

Fig. 1 is a front elevation of a safe embodying a locking mechanism constructed in accordance with the invention, the front plates of the doors being removed to show the interior construction,

Fig. 2 is a vertical section taken along the line 2—2 of Fig. 1 and,

35 Fig. 3 is a horizontal section taken along the line 3—3 of Fig. 1.

Fig. 4 is an enlarged fragmentary sectional detail of the pinion and associated mechanism taken substantially along the line 40 2—2 of Fig. 1, showing an old and well known type of lock tumbler mechanism associated therewith.

The safe body is of any usual construction comprising side, top and bottom frame body members 2, 3, 4 and 5, suitably secured together and forming, together with members 6 and 7, the safe inclosure. Suitably hinged within the top and bottom or side members of the body as at 8 and 9 are a pair of doors generally designated 10 and 11, each consisting of a heavy steel backing frame 12 and a front plate 13 secured thereto as by rivets or screws as may be preferable. Mounted against the frame member 12 within one of the doors, in this instance,

within the door 10, is a plate 14 carrying an L-shaped guide member 15 and a second guide member of any suitable shape 16 cut away as at 17 (for a purpose to be described) for the purpose of supporting and guiding 60 a pair or any other suitable number of horizontally slidable bolts 18 and 19 adapted to be received in suitable recesses 20 formed in the cooperating edge face of the opposite door. A vertically movable bolt 21 is slidably carried in guide members 22 and 23 secured to the door frame for engagement with a recess 24 formed in the top frame member 3 of the safe compartment or inclosure.

A plate or bar 25, carrying a rack 26 for cooperative engagement with a pinion 27 rotatably mounted in the door frame members in any suitable manner, is secured to the bolts 18 and 19 as shown at 28 and 29 in order that clockwise movement of the pinion 27 engaging with the rack 26 will slide the bolts 18 and 19 into locking engagement with the recesses 20 in the opposite door and so that counterclockwise movement will release the bolts from their engagement with the opposite door and unlock it. The bolt 18 is provided with a rack 30 adapted to engage with an idling pinion 31 rotatably mounted in the frame of the door, and the bolt 21 is also provided with a rack 32 for cooperative 75 engagement with the pinion 31, while a recess 33 is provided in the bolt 18 for reception of the lower end of the bolt 21 when withdrawn from its recess 24. It will thus be apparent that when the pinion 27 is 80 turned in a counterclockwise direction it will not only release the bolts 18 and 19 from their locking recesses in the door 11 but it will also, through the intermediary of racks 30 and 32 and idling pinion 31, withdraw 85 the bolt 21 from its locking recess 24.

The pinion 27 is rotatably arranged upon a shaft 34 secured to the rear frame member 12 such as is shown in Fig. 2, and the various parts of the bolt operating mechanism and the bolts are so constructed and arranged that an ordinary tumbler operating key, upon insertion in the slot 35, will operate them. The operation may be accomplished without the use of bolt operating handles such as are commonly provided, and the key alone may serve to swing the doors upon their hinges. Preferably, the doors are arranged to be simultaneously opened through mechanism indicated at 36 105 110 115

and particularly described and claimed in my copending application, Serial No. 14,865 filed March 12, 1925. It will be apparent and understood that any lock mechanism 5 whatsoever that may be operated through the medium of a single key is intended to be incorporated in the pinion 27 as such mechanisms are well known in the art.

From the foregoing description, taken in 10 connection with the drawing, it is believed that the construction and operation of the locking mechanism will be clearly understood. It will also be appreciated that, since many variations and modifications 15 may be made of this structure within the spirit of my invention and the scope of the appended claims, I do not desire to be limited to the details of construction and operation shown and described.

20 I claim:

1. A double door locking mechanism for

safes comprising, a key operable pinion, a member, including a rack for engaging said pinion, carrying a plurality of horizontally 25 slidable locking bolts, a second rack carried by one of said bolts, a vertically slidable locking bolt having a rack associated therewith, and a pinion for operatively connecting the two last said racks.

2. A double door locking mechanism comprising, a horizontally movable locking bolt, a vertically movable locking bolt, a key operable lock including a pinion, a rack connected to said horizontally movable bolt and operably connected to said pinion, and 30 mechanism including a second pinion operably connected to said vertically movable bolt for locking and unlocking movements thereof simultaneously with and in the order of locking and unlocking movements of said 35 horizontally movable bolt.

JOSEPH J. MARIOTTI.
